UNITED STATES PATENT OFFICE

WILLIAM SCHEIBEL, OF BRONX, NEW YORK, ASSIGNOR TO BULOVA WATCH COMPANY, INC., OF NEW YORK, N. Y., A CORPORATION OF NEW YORK

DESIGN FOR A COMBINATION RADIO CABINET AND CLOCK

Application filed June 19, 1931. Serial No. 40,272. Term of patent 3½ years.

To all whom it may concern:

Be it known that I, WILLIAM SCHEIBEL, a citizen of the United States, residing at Bronx, county of Bronx, and State of New York, have invented a new, original, and ornamental Design for Combination Radio Cabinet and Clock, of which the following is a specification, reference being had to the accompanying drawings, forming part thereof.

Figure 1 is a front view of a combination

radio cabinet and clock showing my new design.

Figure 2 is a side elevation of the combination radio cabinet and clock shown in Figure 1.

I claim:

The ornamental design for a combination radio cabinet and clock, as shown.

WILLIAM SCHEIBEL.
